United States Patent Office

Des. 224,953
Patented Oct. 24, 1972

224,953

SHAVING CADDY

John C. Stephenson, 1257 Armacost Ave.,
Los Angeles, Calif. 90025

Filed May 25, 1971, Ser. No. 146,856

Term of patent 14 years

Int. Cl. D6—99

U.S. Cl. D6—88

FIG. 3

FIG. 2

FIG. 1

FIG. 1 is a front elevational view of a shaving caddy showing my new design.

FIG. 2 is a side elevational view thereof; and

FIG. 3 is a top plan view thereof.

The broken line representation of a razor, a package of blades and a styptic pencil in FIG. 1 are for purposes of illustration only.

I claim:

The ornamental design for a shaving caddy, as shown and described.
